STRINGED INSTRUMENT GEAR PEG

Josephus B. Thompson, Covington, Ohio, assignor to
Grover Musical Products, Inc., Cleveland, Ohio

Filed Aug. 19 1965, Ser. No. 86,650

Term of patent 14 years

(Cl. D56—1)

Fig. 1

Fig. 2

Fig. 3

FIGURE 1 is a front elevational view of a stringed instrument gear peg, showing my new design, the rear being a mirror image thereof;

FIGURE 2 is a right end elevational view; and

FIGURE 3 is a top plan view thereof.

The dominant features of my new design are shown in solid lines in the drawing.

I claim:

The ornamental design for a stringed instrument gear peg, substantially as shown and described.
